UNITED STATES PATENT OFFICE.

FELIX EBERHART, OF NEWARK, NEW JERSEY, ASSIGNOR TO AMERICAN CAN COMPANY, OF NEW YORK, N. Y., A CORPORATION OF NEW JERSEY.

COATING-MACHINE.

1,266,669.

Specification of Letters Patent. Patented May 21, 1918.

Application filed October 7, 1912. Serial No. 724,232.

To all whom it may concern:

Be it known that I, FELIX EBERHART, a citizen of the United States, residing in Newark, in the county of Essex and State of New Jersey, have invented a new and useful Improvement in Coating-Machines, of which the following is a specification.

This invention relates to improvements in coating machines such as are adapted to coat either by spraying or otherwise, can ends or other articles.

An object of the invention is to provide a coating machine which is adapted to coat or spray can ends of different sizes without the necessity of adjusting any of the parts or without addition to or elimination of parts.

Another object of the invention is to provide a coating machine of the type above indicated, in which the coating or spraying of the can ends or other articles is done under a hood which is provided with means for exhausting or withdrawing the volatile fumes which commonly arise from coating materials such as are used for lacquering or coating can ends.

Another object of the invention is to provide a tank for collecting the heavy or solid parts of the coating material which drop through the conveyer or between the interstices of the can ends, thus effecting a saving in material and cost of operation.

The invention furthermore consists in the improvements in the parts and devices and in the novel combinations of parts and devices herein shown, described or claimed.

In the drawing forming a part of this specification, Figure 1 illustrates one form of a machine embodying my improvements, the same being partly in elevation and partly in vertical section. Fig. 2 is a longitudinal, sectional view, taken approximately on a plane coinciding with the upper face of the conveyer, showing in full lines a number of can ends regularly disposed on the conveyer, and in dotted lines, a number of can ends irregularly distributed and arranged on the conveyer. Fig. 3 is an enlarged, detail, sectional view, taken substantially on the line 3-3 of Fig. 1, and Fig. 4 is a detail, enlarged view of a portion of the improved form of conveyer.

In the drawing, 10 denotes the endless conveyer carried by and supported on con-

tinuously rotated sprocket gears 11, 11, the 55 same being adapted to be driven from any suitable source of power (not shown). The conveyer 10, as shown more particularly in Fig. 4, comprises a plurality of link members 12, 12, pivotally connected together 60 and covered by an open mesh wire or gauze 13, the mesh of the wire or gauze 13 being small enough to prevent the smallest size can ends or other articles to be coated from falling therethrough, and yet adapted to 65 support and retain the can ends or other articles with one face of each exposed, no matter how irregularly or disorderly arranged thereon.

The can ends or other articles may be 70 placed upon the conveyer either by an operator or, as shown in the drawing, by allowing the same to feed thereon down a chute 14 leading from a can end punching or other machine. The conveyer 10, with 75 the can ends or other articles thereon, is adapted to pass through an inclosed hood or chamber 15, the latter being provided at the bottom thereof with a collecting tank 16, adapted to be emptied or drained as by 80 means of a drain cock 17. In the top of the hood 15 are placed two coating devices 18, which, as shown, are in the form of spraying heads provided with adjustable valves 19, each spray head being supplied 85 with the lacquer or other material from a supply tank 20 by means of a pipe 21. For causing the coating material to spray in the manner shown by the dotted lines in Fig. 1, each spray head is connected to a suitable 90 source of compressed air (not shown) by means of an air tube 22. For conducting off or exhausting the volatile fumes which arise from the coating material the hood 15 is provided with a pair of outlets 23 95 communicating with the exhaust pipe 24, the gases or fumes being exhausted to the atmosphere outside of the building by any suitable means such as the fan 25, shown conventionally in Fig. 3.

After the can ends or other articles have been coated, the same are preferably conveyed through a drying oven 26 through which the endless conveyer passes. After the articles have been coated and dried, the 105 same may be taken from the conveyer after the latter emerges from the drying oven by an operator or allowed to fall off of the

conveyer into a suitable receptacle, as the conveyer passes around the sprocket gear 11.

From the foregoing description, it will be seen that with my improved form of conveyer, the articles to be coated may be rapidly fed or placed thereon, and that the operation is continuous and rapid; that the volatile fumes arising from the coating material are drawn off or exhausted to the atmosphere, thus obviating danger of fires or explosions or liability of injury to operators resulting from breathing the fumes; that practically no coating material is wasted, since all of the same which fails to be deposited on the can ends or other articles and carried off thereby, falls through the open work conveyer and is collected to be subsequently reused; that can ends or other articles of various sizes may be sprayed or coated without changing or adjusting any of the parts and without even stopping the machine; and that can ends of various sizes may be coated simultaneously. The apparatus which I have described, is particularly useful in small factories where the expense of a high priced coating machine cannot be afforded, and where only a few hundred or thousand ends of each size are adapted to be coated at a time.

This machine is particularly adapted to the coating of can ends used in forming what are known in the trade as open end or sanitary cans, wherein the end closures are attached to the flanged ends of the can bodies by an interfolded seam or joint. The principal object of coating the interior of such cans is to cover up all metallic surfaces and all abrasions caused by the necessary handling and manipulation during manufacture. As is well known, commercial tin plate is composed of sheet steel carrying a thin coating of pure metallic tin applied in a molten condition. In the coating of tin plate it is the intention and the endeavor to cover every bit of surface of the steel sheet with the tin, but this is seldom accomplished owing to minute specks of oxidization or imperfections that seem impossible to eliminate; therefore, every sheet of commercial plate has more or less of its surface, comprising spots readily visible to the eye down to microscopic spots, uncoated, and subject to attack from the acids of food products when the sheets are made into cans.

Also, in forming can ends with dies the tin coating is more or less ruptured at the bends and angles, thus further exposing the steel surfaces to oxidizing action.

It is desirable to coat the surface of the can ends immediately after they are formed, so as to completely cover all abrasions, ruptures or exposed spots with an impervious substance or lacquer that is preferably acid and alkali proof and thus create a surface on the inside of food containers that will ef-

fectively protect the metals of the container against the corrosive action of the contents.

The construction and arrangement of this machine is such that it will successfully handle a coating material of a heavy nature, 70 and operate continuously without interference from gumming up.

The conveyer constructed of very open meshwork permits excess coating material to pass through and be collected for further 75 use and such as remains on the meshwork of the conveyer is continuously being baked thereon into a hard smooth surface which is a very essential feature, otherwise the surfaces of the can ends resting on the conveyer 80 would become streaked with the coating material and present an unsightly appearance; besides they would stick to the conveyer and cause no end of trouble, if the adhering coating was not baked onto the conveyer mesh-work each time it passed through the oven. Of course, in time the mesh-work will become heavily charged with the accumulated 85 coatings and will require cleaning, which is easily done by immersion for a time in a 90 suitable solvent.

If the conveyer was made with a solid or unbroken surface instead of a large open mesh, the accumulation of coating material on the conveyer surface would be so rapid, 95 and would build up so fast, that it would be next to impossible to bake it hard each time it passed through the oven and it would soon become a mass of gummy, sticky substance and prevent further operation of the 100 machine.

Coatings of this nature and for this purpose require highly volatile and odorous solvents and suitable provision must be made for carrying away the fumes arising from 105 the spraying station and the baking oven.

In machines for coating can ends that require a baking operation to effect the drying and hardening of the coating, that have article holders or mechanism for controlling 110 or separating the articles, soon become inoperative from the excess accumulation of coating material on the machine parts. These parts, from the nature of their requirements must be constructed of stiff and 115 rigid metal and consequently have so much body that they heat slowly when passing through the oven and thereby prevent the coating they carry from baking to a hard smooth surface, so that it is always sticky, 120 collects dirt and dust, and causes a direct interference with the proper baking of the articles or can ends carried thereby.

A can end is made of thin metal and is quickly heated to the temperature of the 125 baking or drying oven; it is necessary to have the conveying mechanism equally thin, so that the adhering coating is baked hard each time it passes through the oven, thereby presenting a smooth hard surface to the 130

entering can ends and permitting continuous operation. The construction of my conveyer being of very thin rods, strips, or perforated material, none of which need be 5 much thicker than the tin plate, will heat quickly and thereby facilitate the baking operation.

Owing to the fact that I have entirely 10 eliminated individual can end holders of every description, and constructed a flat top conveyer of skeleton construction, I am enabled to coat and bake can ends of different size and of different character at the same time without any change or addition to any 15 of the mechanism, and also produce a machine that will operate continuously for a long period without interference from the coating material and produce coated can ends that are entirely coated on one side and 20 entirely free from coating material on the other side.

Various changes and modifications may 25 be made in the details and arrangement of the parts without departing from the spirit 30 of the invention, and all such changes and modifications are contemplated as fall within the scope of the claims appended hereto.

I claim:—

1. In a machine for lacquering sheet metal 35 articles of various sizes and irregularly distributed, in combination: an endless conveyer consisting of flat and shelf like members, each member comprising a flat section of open mesh wire and pivots connecting 40 said members, one limb of said conveyer when extended, forming a flat support; means for supporting and actuating said endless conveyer; a coating chamber inclosing the article-supporting limb of said conveyer; means within said chamber for applying lacquer in the form of a spray to the 45 sheet metal articles; means at the lower part of said chamber for collecting the excess lacquer; means for withdrawing fumes from the said chamber; and a drying oven inclosing the said supporting limb of the conveyer.

2. In a machine for lacquering sheet metal 50 articles of various sizes and irregularly distributed, in combination: an endless conveyer consisting of flat and shelf like members, each member comprising links, pivots connecting said links and a flat section of open mesh wire connected with the said pivots, one limb of said conveyer when extended, forming a flat support; means for supporting and actuating said endless conveyer; a coating chamber inclosing the article-supporting limb of said conveyer; means within said chamber for applying lacquer 55 in the form of a spray to the sheet metal articles; means at the lower part of said chamber for collecting the excess lacquer; means for withdrawing fumes from the said chamber; and a drying oven inclosing the 60 said supporting limb of the conveyer.

3. In a machine for lacquering sheet metal articles of various sizes and irregularly distributed, in combination: an endless conveyer consisting of flat and shelf like members, each member comprising links, pivots 70 connecting said links and a flat section of open mesh wire connected with the said pivots, one limb of said conveyer when extended, forming a flat support; means for supporting and actuating said endless conveyer; a coating chamber inclosing the article-supporting limb of said conveyer; a chute for feeding sheet metal articles to the said limb of the conveyer in advance of said coating chamber; means within said chamber 75 for applying lacquer in the form of a spray to the sheet metal articles; means at the lower part of said chamber for collecting the excess lacquer; means for withdrawing fumes from the said chamber; and a 80 drying oven inclosing the said supporting limb of the conveyer.

4. In a machine of the character described, in combination: an endless conveyer comprising a plurality of links pivotally 90 connected together and covered by an open mesh wire whereby the conveyer is adapted to support articles of various sizes and irregularly distributed and arranged thereon; and means for applying a coating of liquid 95 material to the articles while the same are on the conveyer; and a receptacle for excess coating arranged under the carrying limb of open mesh wire of said conveyer; substantially as specified.

5. In a machine for coating can heads and other articles, in combination: a conveyer having an article-supporting surface of openwork wire mesh for conveying the articles to be coated; means for spraying and 100 coating the articles arranged above one limb of the said conveyer; a hood inclosing said spraying means and said limb of the conveyer; means in the lower part of said hood beneath said limb of the conveyer for collecting the excess of coating which passes through the conveyer; exhausting means for carrying away fumes from within said hood; and a drying oven arranged beyond the said hood and inclosing the said limb 105 of the conveyer.

6. A machine for coating can ends, comprising a spraying station; a drying or baking station; and a surplus spray collecting receptacle; a conveyer member constructed 110 of relatively thin material to form an open mesh structure, and adapted to receive on its surface in disarranged order can ends to be coated, said conveyer being movable past said spraying station, said collecting receptacle and through said drying or baking oven; means for projecting a spray of coating material onto can ends being conveyed and onto the exposed parts of said conveyer 115 and into said receptacle; and means for 120

125

130

heating said baking oven to a temperature sufficient to harden and bake the sprayed coating on said can ends and on said conveyor during their passage therethrough.

5 7. A machine for coating can ends, comprising a spraying station; a drying or baking station; and a surplus spray collecting receptacle; a continuously movable conveyer member constructed of relatively thin material forming an open mesh structure and adapted to receive on its surface in disarranged order can ends to be coated, said conveyer being movable past said spraying station, said collecting receptacle and

10 15 through said drying or baking oven; means for projecting a spray of coating material onto can ends being conveyed and onto the exposed parts of said conveyer and into said receptacle; and means for heating said baking oven to a temperature sufficient to harden and bake the sprayed coating on said can ends and on said conveyer during their passage therethrough.

20

8. A machine for coating can ends, comprising a spraying station; a drying or baking station; and a surplus spray collection receptacle; a continuously movable horizontal conveyer member composed of relatively thin strips or rods forming an open mesh structure, and adapted to receive on its surface in disarranged order can ends to be coated, said conveyer being movable past said spraying station, said collecting receptacle and through said drying or baking oven; means for projecting a spray of coating material onto can ends being conveyed and onto the exposed parts of said conveyer and into said receptacle; and means for heating said baking oven to a temperature sufficient to harden and bake the sprayed coating on said can ends and on said conveyer during their passage therethrough.

9. A machine for coating can ends, comprising a spraying station; a drying or baking station; and a surplus spray collecting receptacle; a conveyer member composed of relatively thin material forming an open mesh structure; means for placing on its surface in disarranged order can ends to be coated, said conveyer being movable past said spraying station, said collecting recep-

tacle and through said drying or baking oven; means for projecting a spray of coating material onto can ends on said conveyer and onto the exposed parts of said conveyer and into said receptacle; and means for heating said baking oven to a temperature sufficient to harden and bake the sprayed coating on said can ends and on said conveyer during their passage therethrough. 60

10. A machine for coating can ends, comprising a spraying station; a drying or baking station; and a surplus spray collecting receptacle; a continuously moving conveyer member composed of relatively thin material forming an open mesh structure; means for placing on its surface in disarranged order can ends to be coated, said conveyer being movable between said spraying station and said collecting receptacle and through said drying or baking oven; means for projecting a spray of coating material onto can ends being conveyed, and onto the exposed parts of said conveyer and into said receptacle; and means for heating said baking oven to a temperature sufficient to harden and bake the sprayed coating on said can ends and on said conveyer during their passage therethrough. 70 75 80 85 90 95 100

11. A machine for coating can ends, comprising a spraying station and an exhaust station; a drying or baking station; and a surplus spray collecting receptacle; a conveyor member composed of relatively thin material forming an open mesh structure, adapted to receive on its surface in disarranged order can ends to be coated and movable past said spraying station, said collecting receptacle and through said drying or baking oven; means for projecting a spray of coating material onto can ends being conveyed and onto the exposed parts of said conveyor and into said receptacle; and means for heating said baking oven to a temperature sufficient to harden and bake the sprayed coating on said can ends and said conveyor during their passage therethrough.
